1 Claim. (Cl. 257—245)

The present invention relates to improvements in plate type heat exchangers utilized for the transmission of heat between two confined fluids, and particularly it relates to an improved form of "envelope" component to be assembled in multiples for forming such a heat exchanger.

One type of heat exchange apparatus for the transfer of heat between two confined fluids comprises a plurality of spaced metallic plates forming passages through alternate ones of which a relatively hot gas flows in heat exchange relationship with air or other fluid to be heated that in turn traverses the intermediate passages. In many such heat exchangers a series of envelopes are provided each comprising a pair of parallel plates with the space therebetween closed along one pair of opposite edges to bound the sides of the passage for one of the fluids such as air to be heated. The envelopes are mounted in spaced parallel relation to form therebetween the passages for a second or heating fluid, the inter-envelope spaces being closed along one pair of opposite side edges to direct the flow of fluid therethrough. Such spaced envelopes form a core that is usually enclosed within a housing that is provided with inlet and outlet manifolds leading to and away from the gas and air passages through the heat exchanger.

Heat exchangers of this general type are usually provided with extended surface in the form of fins extending into the path of fluids and serving to increase the conduction of heat to and through the walls bounding the passages. These fins have been formed variously from sinuously formed wires or channel members lying adjacent the passage walls in a direction generally parallel to the flow of fluid. To provide good heat transfer between extended surface elements, good bonds must be provided between elements, and it has therefore been customary to braze the elements integrally together into an envelope for assembly into a composite heat exchanger.

Heat exchanger devices of the general type defined possess good heat transfer characteristics and they furthermore have adequate strength and resistance to creep and corrosion to bear up under substantial temperature and pressure. However, there is a growing demand for a plate type heat exchanger having characteristics making possible its use in regions of extreme temperature and pressure.

More specifically it may be stated that the code for pressure vessels as formulated by the American Society of Mechanical Engineers specifies that brazed pressure vessels may not be used at service temperatures in excess of 406 degrees F. Therefore a primary objective of this invention is to provide an improved form of extended surface arrangement for a plate type heat exchanger which may safely be used at conditions of elevated temperature and pressure.

A second object of this invention is to provide a plate type heat exchanger having a minimum number of com-

2

ponent parts which may be readily and economically assembled into an integral unit.

It is a further object of this invention to provide a plate type heat exchanger wherein bonds between component parts thereof that are in a state of tension are formed by a process of welding, while those bonds that are maintained under compression may be produced by more conventional procedures.

The invention will be best understood upon consideration of these objects when viewed in conjunction with the accompanying drawings in which:

Figure 1 is a perspective view of a preferred form of heat exchange envelope defined by this invention.

Figure 2 is a transverse sectional view of a modified form of the invention.

Figure 3 is a transverse view of a further modified form of the invention.

Figure 4 is a perspective view of a plurality of envelopes bonded into an integral heat exchanger.

20 As indicated in the drawings two heat exchange plates 12 are spaced apart by a series of metallic tubes 14 having a rectangular cross section whereby opposite sides thereof abut said plates and the sides normal thereto extend perpendicularly between plates to provide a series of 25 longitudinal fins extending through the passageway 15 therebetween.

The tubes may be spaced apart as illustrated in Figure 1 or they may otherwise be placed in lateral abutment as illustrated in Figure 3 to provide longitudinal fins between plates of either single or double strength. The extended surface on the outer side of each envelope wall 12 comprises a metallic plate 16 having rows of apertures 22, the material from which remains as a series of tabs or interrupted fins 24 attached to one side 35 of the aperture and then bent out from the surface thereof.

Further variation in the precise arrangement of elements within an envelope may be had by elimination of plate 12 entirely as is illustrated in Figure 3, since the sides 18 of tubes 14 which lie in end-to-end abutment provide a passage wall that precludes the necessity of an additional wall member illustrated by plate 12 of Figure 1.

45 A still further variation is shown in Figure 2 where a corrugated sheet is utilized to replace the tubular elements of Figures 1 and 3. The corrugated sheet is preferably formed with a series of substantially vertical risers 28 extending between crests 32 which abut the spaced plates 12 on which the sheets 16 of interrupted 50 strip fins are positioned. Assembled in this manner the risers 28 provide a series of imperforate fins extending between plates 12 while the members 24 provide a series of interrupted strip fins on the opposite side thereof to effect an efficient transfer of heat between fluids on opposite sides of said plates.

In assembling envelope units of the type illustrated in Figures 1, 2 or 3 no special supports or jigging fixtures are required since the elements when assembled are inherently stable and the assemblies may be readily bonded into integral units by a process of brazing. As is customary, thin sheets of brazing material 34 are inserted during assembly between surfaces to be bonded and on being heated to a brazing temperature the brazing material fuses and is drawn into the interstices between 60 abutting elements by a process of capillarity.

When certain alloy steels are used as envelope components normal brazing procedures are often times not effective because of the necessity for highly critical atmospheric conditions that must be maintained in the space surrounding the envelope during the brazing operation. Therefore, in the bonding of "stainless" steel and

other high temperature alloys, various ceramic adhesives may effectively replace the metallic brazing material as a bonding agent and as an aid to the conduction of heat between abutting elements.

After the envelope assembly has been bonded into an integral unit, closure bars 36 are inserted between plates 12 along a pair of opposite sides thereof parallel to the rows of tubing 14 and are welded continuously thereto. This welding operation may be readily carried out automatically as exemplified by automatic seam welding or submerged arc welding procedures.

After the closure bars 36 have been welded in place between sides of individual envelopes, a series of envelopes are joined together by welding a series of closure bars 38 normal to bars 36 between ends of adjacent envelopes in the manner shown in Figure 4. The space between envelopes thus bonded together by welding becomes a fluid passageway 42 having a series of interrupted strip fins 24 protruding thereinto. A series of envelopes so joined together then becomes a "bundle" of envelopes which may be handled as a unit for further assembly.

After assembly in this manner the bundled elements are enclosed in a housing having unitary sides 45 with composite sides normal thereto, the latter sides being built up by welding a series of metallic strips 48 in side-to-side relationship. The strips 48 are sized to extend laterally a distance equivalent to the distance between adjacent closure bars 36 or a predetermined multiple thereof in such a manner that the welds 52 joining strips 48 together are aligned with the closure bars and may be made integral therewith by the process of welding.

One of the composite sides of the housing is provided with an inlet 54 and an outlet 56 whereby a fluid under high pressure may be admitted and exhausted from the series of passageways 42 between envelopes that are formed by welding the closure bars 38 between envelope walls. Simultaneously a low pressure fluid as may be exemplified by combustion gases is directed through the passageways 15 within the series of envelopes, the difference in pressure of the two fluids resulting in a force component which places the welded joints between envelopes in a state of tension while the tubes 14 together with their brazed joints are placed under compressive force.

The completed housing may be further encased in a

strong-back assembly which is sized to afford added strength to the housing as may be required to safely contain conditions of elevated temperature and pressure.

While this invention has been described with reference to the several embodiments illustrated in the drawing it is evident that various changes may be made without departing from the spirit of the invention and it is intended that all matter contained in the above description or shown in the accompanying drawings shall be interpreted as illustrative and not in a limiting sense.

What we claim is:

Heat exchange apparatus adapted to transfer heat between two confined fluids comprising in combination a series of envelopes that include unitary walls spaced apart by ligaments and having a pair of side closure bars at the sides thereof parallel to the ligaments and adapted to enclose a first passageway therethrough for a low pressure fluid; end closure bars welded normal to the side closure bars between opposite ends of adjacent envelopes to provide a series of interenvelope passageways for a high pressure fluid; a metallic plate coextensive with each of said unitary walls bonded thereto and having rows of apertures therein, the material from which comprises a series of interrupted fins attached to one side of the aperture when bent out from the surface thereof; and a housing surrounding the assembled envelopes including a series of plane metallic strips welded continuously along their sides to the intermediate portion of the side closure bars and spaced from the ends of the end closure bars to define ports at opposite ends of the metallic strips for the flow of the high pressure fluid through the inter envelope passageways; and plate members abutting opposite end walls in a series of assembled envelopes adapted to combine with the plane metallic strips lying normal thereto and provide a housing around the envelopes.
